Fig. 2

Fig. 1

To all whom it may concern:

Be it known that we, William R. Tappan and Truman B. Clark, have invented a new, original, and ornamental Design for a Range, of which the following is a specification, reference being had to the accompanying drawing, forming a part hereof.

Fig. 1 is a left front perspective view of the range embodying our new design with the cover for the surface units in open position; and

Fig. 2 is a right front perspective view thereof with the cover in closed position.

The openings are shown only on part of the upper front grill and on part of the sides of the top portions. It is to be understood that they cover the entire areas shown.

The dominant features of our design reside in the portions shown in full lines.

We claim:

The ornamental design for a range, as shown and described.
